UNITED STATES PATENT OFFICE

2,297,120

DEVICE FOR GLUING MULTI-PLY
PRODUCTSWilliam H. Wilson and George A. Ordway,
Burlington, Vt.

Application September 14, 1940, Serial No. 356,860

2 Claims. (Cl. 144—281)

This invention relates to the manufacture of multi-ply products, such as spool heads, and relates more particularly to the effective securing of the plies of such products to each other. Certain new types of glue are now available which possess improved and very desirable qualities, such as water-proofness, but these new glues require not only pressure but also a substantial degree of heat in their application, in order to produce satisfactory results.

It is the general object of our invention to provide an improved method of gluing multi-ply products, by which method superposed plies of reasonable area may be quickly and firmly secured together, even when a glue is used which requires a considerable degree of heat, in addition to pressure during setting, such as a thermo-plastic glue.

A further object of our invention is to provide improved devices for practicing our improved method. More specifically, we provide special discs or plates to be interposed between multi-ply products, which discs or plates are so formed that hot air or vapor may circulate readily therethrough and between said products, thus conveying heat in substantial quantities over the adjacent areas of said products while at the same time continuous and substantial pressure may be conveniently maintained on said products.

In the preferred form, the plates or discs are of a sheet metal having good heat conductivity and are corrugated or otherwise formed to provide air-conducting cross channels or passages between adjacent spool heads. In the following description and claims, the term "air" is to be understood as including also any other gas or vapor which forms a suitable heat-transferring medium.

Our invention further relates to arrangements and combinations of parts which will be herein-after described and more particularly pointed out in the appended claims.

Preferred forms of the invention are shown in the drawing, in which

Fig. 1 is a side elevation of a spool head assembly, embodying our improvements;

Fig. 2 is a plan view of one of the corrugated discs shown in Fig. 1;

Fig. 3 is a plan view of a modified form of air-conducting disc; and

Fig. 4 is a plan view, looking in the direction of the arrow 4 in Fig. 3.

Referring to Fig. 1, we have shown a plurality of multi-ply spool heads H assembled on a rod 10 having a head 11 at one end and having an

elongated slot 12 in its opposite end portion. A heavy cast iron washer 14 is placed above the rod head 11, and a second and similar washer 15 is placed under a wedge or key 16 which extends through the slot 12 in the rod 10.

Air-conducting sheet metal discs 20 are inserted adjacent each washer 14 or 15, and also between each two adjacent heads H. These discs 20 are stamped from relatively heavy sheet metal which has grooves or corrugations 22 (Fig. 2) extending across the same in parallel relation. When a disc is stamped from such a corrugated sheet, the grooves form unobstructed air-conducting passages extending across the disc from edge to edge thereof.

The sheet metal from which the discs are made is to be sufficiently heavy so that it will resist displacement and will permit a heavy pressure to be applied to the heads H by driving in the wedge 16.

After a plurality of heads H and discs 20, with washers 14 and 15, have been thus assembled and firmly secured on a rod 10, the assembly is placed in an oven or is otherwise so disposed that a stream of highly-heated air or vapor will circulate about the assembly and particularly through the grooves or corrugations 22.

The hot air passing through these corrugations quickly heats the metal and the heat is transferred through the metal to the adjacent spool heads, which in turn are heated sufficiently to cause the glue interposed between the plies of the head to set and firmly adhere. The setting of the glue thus takes place under both heat and pressure, which is a requisite for certain modern kinds of glue, such as thermo-plastic type. Active circulation of the hot air will accelerate the setting action.

In Figs. 3 and 4 we have shown a modified air-conducting and heating member comprising upper and lower plates 30 and 31 secured together in spaced relation by studs 32. With this construction, any desired amount of air-conducting space can be secured by varying the length of the studs 32 and the entire adjacent surfaces of the spool heads contact heated metal instead of part metal and part air, as in the construction previously described.

With either construction, the condition of the atmosphere in which setting of the glue occurs can be accurately controlled and the atmosphere may be dry for a quick setting operation, or may contain a certain amount of moisture so that the wood of the spool heads will remain more or less in normal condition during setting.

While the drawing shows two-ply spool heads only, a larger number of plies can be used when desired.

Having thus described our invention and the advantages thereof, we do not wish to be limited to the details herein disclosed, otherwise than as set forth in the claims, but what we claim is:

1. A spacing device for use in gluing superposed multi-ply products which comprises a generally flat impervious metal separating member of substantial surface area and having transverse air-conducting passages formed therein and parallel to the flat surfaces of said member and extending from edge to edge thereof, each passage

being continuous from edge to edge of said member and being freely open at both ends thereof.

2. An article of manufacture to be used in gluing superposed multi-ply products which comprises a sheet metal plate having corrugations extending across said plate on the opposite sides thereof and forming continuous cross passages through which air may circulate parallel to the general plane of the surfaces of said plate, and said passages being freely open at each edge of said plate.
